UNITED STATES PATENT OFFICE

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY

DEVICE FOR ATTACHING HEELS

Original application filed December 14, 1922, Serial No. 606,880. Divided and this application filed June 27, 1928. Serial No. 288,620.

This invention relates to devices for attaching heels to shoes and will be explained, for the purpose of illustration, by describing an embodiment of the invention in a fastening device employed in the attachment of wood heels to women's shoes, although it should be understood that the utility of the invention is not limited to the attachment of wood heels.

In United States Letters Patent No. 1,615,258, granted January 25, 1927, on application of M. V. Bresnahan, there is described a method of temporarily attaching wood heels to shoes by passing a screw fastener through a hole in the rear end of a last in a shoe and through the heel-seat portion of the shoe bottom into a heel, to secure the last, the shoe and the heel together so that various operations can be performed upon the heel or the shoe without waiting for heel attaching adhesive to dry. In accordance with this method not only is the heel securely held in place against the heel seat of the shoe during the drying of the adhesive but the shoe and last are clamped together in such a manner that the last distributes the clamping pressure over the entire heel-seat portion of the shoe. Thus, the latter is compressed between the heel and the last to conform the heel seat to the attaching face of the heel under pressure, thereby insuring firm seating of the heel and the provision of a tight joint between the shoe upper and the rim around the attaching face of the heel.

An object of the present invention is to provide an improved fastening device which, while retaining all the advantages of the Bresnahan screw fastener, will simplify the equipment necessary for the attachment of heels under usual shoe factory conditions by eliminating the necessity of providing fasteners of different lengths for lasts of different heights.

To this end, the invention, in one aspect, provides a heel fastening device having a shank adapted to extend through a last, a threaded portion at one end of the shank to engage a heel, a driver-engaging head at the opposite end of the shank, and a last engaging member movable on the shank. In the

illustrated embodiment of the invention the last engaging member takes the form of a nut threaded upon the shank portion of the fastening device and movable into clamping engagement with the last after the threaded end of said device has been screwed into a heel positioned upon a shoe mounted upon the last. The same fastening device may thus be used with lasts of different heights.

Another object of the invention is to provide an improved fastening device which will facilitate the attachment of heels without the use of adhesive, and will effect further improvement in the attachment of heels, whether with or without the use of adhesive.

Accordingly, in another aspect of the invention, there is provided a compound fastening comprising a heel engaging part and a last engaging shank formed with interengaging portions. The heel engaging part may consist of a screw adapted to serve as a permanent heel fastening while the shank, after being utilized to drive the screw and clamp the last thereto, may be disengaged from said screw and removed. Thus, if it is not desired to employ adhesive in the attachment of the heel, the last or the heel end portion of the last may be removed from the shoe without disturbing the attachment of the heel, to facilitate the driving of heel attaching nails from the inside of the shoe into the heel, for example. Otherwise, if adhesive be used, any desired operations may be performed before the adhesive is dry, regardless of whether or not the heel end portion of the last is removed. Moreover, the insertion of a permanent heel fastening into the central portion of the heel supplements the heel attaching nails and strengthens the permanent attachment of the heel.

Other objects and features of the invention will be understood and appreciated from reading the following detailed description of one embodiment thereof in connection with the accompanying drawings, in which

Fig. 1 is a view in side elevation, with parts broken away, showing a fastening embodying the invention inserted through a last into a heel;

Fig. 2 is a view showing the last clamping

nut screwed into engagement with the last; Figs. 3 and 4 are, respectively, top and side views of one of the permanent heel fastening parts;

5 Figs. 5 and 6 are, respectively, top and side views of a modified form of permanent heel fastening part; and

10 Figs. 7 and 8 are, respectively, top and bottom plan views of the separable shank part of the compound fastening device.

In preparation for the use of the improved fastening device illustrated in the drawings, a last, a shoe and a heel are preliminarily clamped together by means fully illustrated 15 and described in United States Letters Patent No. 1,664,657, granted April 3, 1928, upon my application. As shown in Fig. 2, the heel is firmly supported by a tread plate 10 and a vertically adjustable rear support 12, carried by a post 14 mounted on a table or bench.

20 While the last, shoe and heel are held preliminarily clamped as described, a drill is inserted through a hole passing through the rear end of the last and is guided by the hole 25 in the last to drill a hole of predetermined depth through the heel seat of the shoe into the heel. After the heel has been prepared by drilling a hole, as above described, my improved fastening device is inserted in the hole 30 in the last. This device comprises an upper, or shank, part 20 having a driver-engaging reduced head 22 (Figs. 1 and 7) and a central threaded stem 24 (Fig. 8) on its lower end. The stem 24 is arranged to seat in a threaded 35 hole 26 formed in the head 28 of a permanent heel fastening such as a threaded screw 30. If desired, a slot 32 (Fig. 5) may be formed in the head 28 of the screw so that the screw may be removed without undue 40 difficulty if it is necessary to remove the heel in repairing the shoe. The upper or shank part 20 and the screw 30 are threaded together before insertion in the hole in the last, and the head 22 may be engaged by a 45 power-driven, screw-inserting implement 34 constructed as described in the above identified Letters Patent No. 1,664,657. The parts are held in the relative positions shown in Fig. 1, until the screw 30 is driven home, 50 with its head substantially flush with the upper surface of the sole of the shoe.

In order to clamp the last firmly to the permanent heel fastening 30, a last clamping nut 36 is threaded on the upper end of the 55 shank part of the driving member 20 in such a manner that it may be turned into clamping engagement with the top of the last. Preferably, a leather or other compressible washer 38 is provided between the nut 36 and the last. As shown in Fig. 2, the nut 36 may be turned by a socket wrench including a manipulating handle 40 in which a wrench member 42 is mounted for turning movement. 60 The wrench member 42 is formed at its lower end to engage the sides of the last clamping

nut 36 and is provided with a cylindrical recess 44 to avoid the possibility of engaging the head 22 of the driving member 20. The wrench member is also formed with an upwardly projecting head 46 of substantially the same form as the head 22, adapted to be engaged by the implement 34 to operate the wrench to turn the last clamping member 36 firmly down against the top of the last. The last, the shoe and the heel having been firmly clamped together, as shown in Fig. 2, various finishing or other operations may be performed upon the shoe in any desired manner. The screw driving shank portion 20 of the fastening device is withdrawn, when desired, by turning it in the reverse direction whereupon the stem 24 and the member 20 separate from the recess 26 in the screw 30, leaving the screw 30 permanently securing the shoe and heel together. Thereafter, the last may be removed from the shoe and the heel further secured by inside nailing in the usual way, if desired, or other operations may be performed upon the shoe in any preferred manner.

90 While one form of compound fastening has been particularly described, it should be understood that the scope of the invention is not limited to this specific form but that the invention may be embodied in various 95 modified structures within the scope of the appended claims.

The improved method of making shoes which involves the use of the above-described fastening device is not claimed herein but is 100 described and claimed in my application for United States Letters Patent Serial No. 606,880, filed December 14, 1922, matured into Patent No. 1,722,267, dated July 30, 1929, of which the present application is a division.

Having thus described the invention, what is claimed as new and desired to be secured by Letters Patent of the United States is:

1. A heel fastening device comprising, in 110 combination, a shank adapted to extend through a last, a threaded portion at one end of the shank to engage a heel, a driver-engaging head at the opposite end of the shank, and a last-clamping nut threaded upon the 115 shank.

2. A two-part heel fastening comprising, in combination, a first part constructed and arranged to serve as a permanent heel fastening, and a separable part having a portion interengaging with and carrying said first part and another portion to engage a last and secure it to said first part.

3. A two-part heel fastening comprising, 125 in combination, a first part constructed and arranged to serve as a permanent heel fastening, and a separable part having a portion interengaging with and carrying said first part and another portion including a shank to 130

pass through a hole in a last and a member to engage the top of the last.

4. A two-part heel fastening comprising, in combination, a first part constructed and arranged to serve as a permanent heel fastening, and a separable part having a portion interengaging with and carrying said first part and another portion including a shank to pass through a hole in a last and a member movable on the shank to engage the top of the last.

5. A compound heel fastening comprising, in combination, a heel-engaging screw and a last-engaging shank formed with interengaging separable parts, said shank carrying a last-clamping member.

6. A two-part heel fastening comprising, in combination, a heel-engaging screw and a last-engaging shank threaded together so that the shank will drive the screw into the heel when turned in one direction and will separate therefrom when turned in the reverse direction.

7. A two-part heel fastening comprising, in combination, a heel-engaging screw and a last-engaging shank threaded together so that the shank will drive the screw into the heel when turned in one direction and will separate therefrom when turned in the reverse direction, and a last-clamping member carried by the shank.

8. A two-part heel fastening comprising, in combination, a heel-engaging screw and a last-engaging shank threaded together so that the shank will drive the screw into the heel when turned in one direction and will separate therefrom when turned in the reverse direction, and a last-clamping member movable on the shank to clamp the last irrespective of its height.

9. A two-part heel fastening comprising, in combination, a heel-engaging screw and a last-engaging shank threaded together so that the shank will drive the screw into the heel when turned in one direction and will separate therefrom when turned in the reverse direction, and a last-clamping member threaded on the shank.

10. A heel-attaching device comprising a part to interengage separably with a heel fastening, a part to be engaged by a driver to insert the fastening, and a part to clamp a last to the fastening.

11. A heel-attaching device comprising a screw-engaging threaded stem, a driver-engaging head, and a last-clamping member movable with respect to said stem.

12. A heel-attaching device comprising a screw-engaging threaded stem, a driver-engaging head, a shank carrying the stem and head, and a last-engaging member movable on the shank.

13. A heel-attaching device comprising a screw-engaging stem, a driver-engaging head, a shank carrying the stem and head,

and a last-engaging nut threaded on the shank.

In testimony whereof I have signed my name to this specification.
